UNITED STATES PATENT OFFICE

FRANK B. HAMERLY, OF AURORA, ILLINOIS, ASSIGNOR TO INDEPENDENT PNEUMATIC TOOL COMPANY, OF CHICAGO, ILLINOIS, A CORPORATION OF DELAWARE

LUBRICATING DEVICE FOR PNEUMATIC TOOLS

Application filed June 25, 1931. Serial No. 546,728.

This invention relates to pneumatic tools and more particularly to lubricating means therefor.

The main object of the invention is to provide a lubricating device which can be incorporated in the structure of the tool to hold or contain a supply of lubricant for the working parts of the tool and automatically discharge a predetermined amount of such lubricant into the air supply of the tool on each starting of the tool on opening its throttle valve.

Another object of the invention is to so construct the lubricating device that it will automatically recharge itself from the lubricant supply on each closing of the throttle valve so as to have a charge available for discharge into the tool on each opening of the valve.

20 A further object of the invention is to utilize the air pressure supplied to the tool on opening the throttle valve for operating the lubricating device in its discharging action.

25 A further object of the invention is to employ a plunger in the lubricating device for controlling the discharge of lubricant into the tool and for replenishing the charge on stopping the tool.

30 A further object of the invention is to have the plunger exposed for operation in discharging direction by the action of the air pressure thereon, and be moved in the opposite direction to recharge the device by spring means which operates when the air supply to the tool is turned off as by closing the throttle valve.

The invention consists further in the matters hereinafter described and claimed.

40 In the accompanying drawings—

Fig. 1 is a side view, partly in section, of a pneumatic tool of the hammer type equipped with a lubricant supplying device of my invention;

Fig. 2 is an enlarged longitudinal sectional view through the upper portion of the tool to show the lubricant supplying device, the latter being shown in recharging position;

50 Fig. 3 is a similar view showing the lubri-

cant supplying device in discharging position;

Fig. 4 is a transverse sectional view taken on line 4—4 of Fig. 2;

Fig. 5 is a view similar to Fig. 2 showing another form of my improved lubricant supplying device, the latter being shown in recharging position;

Fig. 6 is a similar view showing the device of Fig. 5 in discharging position; and

Fig. 7 is a transverse sectional view taken on line 7—7 of Fig. 5.

In Fig. 1, 1 indicates the barrel of the tool, 2 the handle at the rear or inner end of the barrel, 3 the chisel or other working element inserted into the front or outer end of the barrel and 4 the hammer piston which by its reciprocation in the barrel delivers the working blows to the chisel 3 in the operation of the tool.

In Fig. 2, 5 indicates the valve mechanism in the barrel for automatically controlling the supply of air pressure to the opposite ends of the barrel for reciprocating the hammer piston 4 therein. The valve mechanism 5 is of the character described and claimed in the application of Reinhold A. Norling, Serial No. 528,044 and needs no further illustration or description herein except to say that the back and forth movement of the valve plate 6 controls the supply of air pressure to the opposite ends of the barrel.

The handle 2 is suitably secured to the inner end of the barrel 1, as by means of bolts 7, 7, and provides a closure cap for such end of the barrel, as shown in Fig. 2. Located in the barrel 1 between the handle 2 and the valve mechanism 5 is the lubricating device of my invention. The device in both of its forms, as shown in Figs. 2 to 4 and 5 to 7, respectively, is held or clamped in the barrel against the valve mechanism 5 by the handle 2.

In Figs. 2 to 3, the lubricating device is indicated generally by 8 and is made to have an oil containing reservoir 9 surrounding the device and which reservoir can be filled with oil or other lubricant of the character required for the working parts of the tool through a filling passage 10 in the portion

of the handle 2 over the inner end of the barrel. Passage 10 is normally closed by a screw or other plug 11. The device 8 has an upright outside wall 12, a bottom wall 13, and a top wall 14, the latter being preferably made integral with the wall 12 by making such parts of the device in cast form. The bottom wall is removably connected to the device, as by screws 15, 15 to the wall 12, so that the interior of the device may be accessible for assembling, cleaning and repair. The top wall 14 has an opening 16 connecting reservoir 9 with filling passage 10, as shown in Fig. 2. The portion of handle 2 over the inner end 15 of the barrel 1 is provided on its under side with a recess 17 to receive the upper end of the device 8 for centering the same in the barrel and with respect to the control valve 5. The recess 17 also holds the device 8 in spaced 20 relation to the surrounding wall of the barrel so that the exhaust chamber 18 about the valve 5 may continue up to and about the device 8. The barrel 1 is provided in its outer wall with one or more ports 19 connecting the exhaust chamber 18 with the atmosphere. 25

The device 8 is provided with a mid-section 20 cast integral with the top wall 14 and extending down through the reservoir 9 to the bottom wall 13. Section 20 is provided 30 with an axial passage 21 extending from top to bottom of the device and connecting at its upper end with the main pressure supply passage 22 in the handle 2. Passage 21 connects at its lower end with a port 23 in bottom wall 35 13, which port connects with the main inlet port 24 in the valve assembly 5, as shown in Fig. 2. By this arrangement, air pressure may enter the tool to reciprocate the piston 4 therein when the manually operable throttle valve 25 in the handle 2 of the tool is depressed or moved into open position. The compressed air for operating the tool is supplied thereto through the handle by a hose 26 connecting the handle on the advance side 40 of the valve, as shown in Fig. 1.

The mid-section 20 of the device 8 is provided with two chambers 27, 28 arranged on opposite sides of the passage 21 and substantially parallel thereto, as shown in Figures 2, 50 3 and 4. Located in chamber 27 is a plunger 29, having an enlarged head 30 at its upper end and which head is exposed through the open upper end of chamber 27 to the air pressure supplied to the tool through the inlet passage 22 in the handle. The handle section 55 over the barrel 1 is recessed as at 31 about the passage 21 and said recess is made large enough in diameter to extend over a portion of head 30 of the plunger so that the latter will be exposed for depression by the air pressure admitted to the tool on opening the throttle valve 25. The portion of the handle section over the remaining part of the head 30 is flush with the upper end of the fixture 8 so as to form a stop for the plunger 60 65

when raised by a coil spring 32 arranged about the stem of the plunger below the head. The lower end of the spring rests on a seat 33 within the chamber 27 and arranged above the port means to be presently described for connecting the lower portion of the chamber 27 with the reservoir 9 and air passage 21, respectively. The portion of the chamber 27 above the seat 33 is substantially equal in diameter to the head 30 of the plunger. The portion of the chamber 27 below the seat 33 is smaller in diameter, being equal to that of the stem of the plunger, the stem having a snug fit in such portion of the chamber to prevent the leakage of lubricant about the same. The upper enlarged portion of the chamber 27 below the head 30 is constantly connected with the exhaust side of the tool to permit movement of the plunger in opposite directions. This connection is made by communicating passages 34, 35 in the section 20 and bottom wall 13, respectively, of the device 8. The passages 34 open into the enlarged part of the chamber 27 just above the seat 33, while the passages 35 open into the exhaust chamber 18 through the peripheral edge of wall 13, as shown in Fig. 4. 70 75 80 85 90

The lower portion of the plunger 29 is provided with an axial passage 36 which opens through the bottom of the plunger as shown in Figs. 2 and 3. The upper end of the passage 36 is connected by a radial port 37 with an angular groove 38 in the stem of the plunger and encircling the same as shown in Figs. 2, 3 and 4. Section 20 is provided with 100 two ports 39, 40, one connecting chamber 27 with reservoir 9 and the other connecting the chamber with air passage 21. Ports 39 and 40 are spaced apart lengthwise of the chamber for alternate opening and closing by the 105 plunger in its endwise movement.

Chamber 28 opens at its upper end into recess 31 and contains an inwardly opening check valve 41 normally held to its seat by spring 42 and closing port 43 which when open connects reservoir 9 with the air pressure supplied to the tool. By this arrangement, the oil or lubricant in the reservoir is under pressure and thus will be supplied to chamber 27 below plunger 29 in any position 110 115 in which the tool may be held.

The lubricating device of Figs. 2 to 4 operates as follows: When the throttle valve 25 is closed, the tool is not under pressure, and spring 32 raises plunger 29 to open port 39 whereby the lower end of chamber 27 as evacuated by the plunger may fill with lubricant from reservoir 9. The amount of lubricant taken into the chamber is limited to the portion of the chamber freed by the plunger and thus a predetermined charge is collected for supply to the working parts of the tool when the plunger is depressed. This occurs as soon as the throttle valve 25 is opened. The air pressure entering the tool will act on 120 125 130

the head 30 of the plunger to depress it, opening port 40 and allowing the plunger to discharge the previously collected charge of lubricant into the air passage 21, where the 5 lubricant will be picked up by the air stream and be carried therewith into the barrel of the tool past the valve 5 to lubricate the movable parts of the valve as well as the piston 4. When the throttle valve 25 is closed, the 10 plunger 29 is raised and another charge of lubricant is collected in the chamber 27 for subsequent discharge into the air stream on the next opening of the throttle valve. As a tool of the character herein shown is only run 15 at short intervals, between each opening and closing of the throttle valve, the lubricant may be injected into the tool in predetermined amounts or charges of the character described, as each charge will well lubricate 20 the working parts of the tool during the short intervals that the tool is actually run. With the amounts of lubricant supplied to the tool controlled to measured charges, wasting of the lubricant is prevented, as there is no supply of lubricant to the tool when the tool is 25 not in operation. By automatically supplying pre-determined amounts of lubricant to the air stream, it is possible to secure the proper amount of oil for lubrication instead 30 of depending on an ejector action which is likely to become clogged and therefore cut off the oil supply to the tool. Moreover, by having the lubricating device operated by the pressure supplied to the tool, certainty of 35 action is secured with sufficient force developed to discharge the collected charge of lubricant into the air stream on each starting of the tool. Furthermore, the structure shown and described is simple in construction 40 and operation and is of a character which may be readily and easily embodied in the interior of the barrel of the tool without materially increasing the overall length of the barrel or changing its general appearance. 45 In the form of the device shown in Figs. 5 to 7, the plunger 44 is arranged to be raised instead of lowered when discharging the collected charge of lubricant into the air stream. The chamber 45 for the plunger is connected 50 at its lower end with the air passage 46 by a port 47. The lower face of the plunger is provided with a rib or projection 48 so that when the plunger is against the upper face of the bottom wall 49 of the device 50, there is 55 sufficient clearance between the bottom wall and the lower end of the plunger to permit the air pressure to enter below the plunger for raising the same. The reservoir 51 is connected with the chamber 45 by a slot like port 60 52, which, as shown in Fig. 5, opens into the chamber 45 between the heads 53, 54 at the opposite ends of the plunger when the latter is in its lowermost position. The lower head 53 is the larger and opens the port 52 when 65 the plunger is lowered by its spring 55, and

closes the port when the plunger is raised by air pressure, as shown in Fig. 6. The stem of the plunger between its heads is reduced in diameter so that when the plunger is raised, the charge of lubricant collected in chamber 45 above head 53 may be discharged into air passage 46 through port 56. Upper head 54 of the plunger closes this port when the plunger is lowered to gather a charge of lubricant. The upper end of chamber 45 is closed by the handle 2. The portion of the chamber 45 above head 54 is vented to the exhaust side of the tool by passages 57, 58 in the mid-section 59 and bottom wall 49, of the fixture 50, as shown in Fig. 7.

The rest of the structure shown in Figs. 5 to 7, is the same as the corresponding parts shown in Figs. 2 to 4, and like parts are indicated by like reference characters. In both forms of devices, the device recharges when the throttle valve is closed and discharges when the valve is opened.

The details of structure and arrangement of parts shown and described may be variously changed and modified without departing from the spirit and scope of my invention, except as pointed out in the appended claims.

I claim as my invention:

1. In a pneumatic tool, a throttle valve for controlling admission of pressure fluid into the tool, a lubricant containing reservoir, a chamber having larger and smaller portions, inlet and discharge ports for the smaller portion of the chamber with the inlet port connected with the reservoir, a plunger having a head in the larger portion of the chamber and a stem in the smaller portion thereof to control the opening and closing of said ports, spring means in the larger portion of the chamber and engaging the head of the plunger to act thereon on the closing of the throttle valve to move the plunger in a direction to close the discharge port and open the inlet port whereby the chamber may take in a charge of lubricant from the reservoir, the head of the plunger being acted on by the pressure fluid admitted in the tool on the opening of the throttle valve for moving the plunger in a direction to close the inlet port and open the discharge for discharging the lubricant from the chamber through said discharge port into the path of the pressure fluid supplied to the tool, said stem having a passage and connected annular groove for connecting the smaller portion of the chamber with the discharge port when the plunger opens the same, and means for venting the large portion of the chamber occupied by the spring to the exhaust side of the tool.

2. In a pneumatic tool having a barrel with the working parts of the tool therein, a handle secured to and closing one end of the barrel, a throttle valve in the handle for controlling the admission of pressure fluid into

the barrel, and a lubricating device for the tool located in the barrel between the handle and working parts of the tool, said device having a surrounding wall and a mid-section 5 forming a lubricant containing reservoir, said mid-section having a pressure fluid passage and a lubricant containing chamber, the latter serving to collect a predetermined charge of lubricant from the reservoir on the closing 10 of the throttle valve, and a plunger for the chamber and operable by the pressure fluid admitted into the barrel on the opening of the throttle valve for discharging the previously collected charge of lubricant from the 15 chamber into said pressure fluid passage for lubricating the working parts of the tool, said plunger having its end adjacent the handle partially exposed to the action of the pressure fluid and its remaining portion arranged 20 for contact with the handle to provide a stop for the plunger.

3. A lubricating device for use in pneumatic tools, comprising a mid-section, an outside wall surrounding the same, top and bottom walls closing the space between the outside wall and the mid-section and forming therewith a lubricant containing reservoir, said mid-section having a lubricant collecting chamber and two pressure fluid passages, one 30 opening through the top and bottom walls and the other opening through the top wall and into the reservoir, inlet and discharge ports connecting the chamber with the reservoir and the first of said pressure fluid passages, respectively, a plunger operable in said chamber for alternately opening and closing said ports, and spring means for moving the plunger in a direction for opening the inlet port and closing the discharge port, 40 said plunger being exposed for operation by the pressure fluid supplied to the tool for moving the plunger in the opposite direction, and check valve for the other pressure fluid passage.

45 In testimony whereof I affix my signature.
FRANK B. HAMERLY.
